UNITED STATES PATENT OFFICE

PETER FIREMAN, OF TRENTON, NEW JERSEY, ASSIGNOR TO MAGNETIC PIGMENT COMPANY, OF NEW YORK, N. Y., A CORPORATION OF NEW YORK

ELECTROLYSIS

Application filed May 9, 1927. Serial No. 189,822.

This invention relates to electrolysis, and particularly to the production of alkalies and metallic salts in a single electrolytic operation, the alkali and salt solutions being re-
5 covered separately.

In the production of metallic salts and alkalies by electrolysis difficulty is encountered because of the interdiffusion of these products. Thus, if ferrous chloride and sodium
10 hydroxide, for example, are produced in the same cell the interdiffusion results in a precipitate of ferrous hydroxide. The accumulation of such a precipitate in the cell rapidly reduces the efficiency thereof. The cell
15 quickly becomes inoperative and must be emptied and cleaned.

In United States Letters Patent No. 1,490-
372, issued April 15, 1924, I have described an
20 electrolytic cell and the method of operating
such a cell to produce solutions of metallic
salts and of alkalies such, for example, as
ferrous chloride and sodium hydroxide by
electrolysis of a solution of sodium chloride
25 in the presence of an iron anode. The cell
described in the patent is divided by a sepa-
rator into anode and cathode compartments.
The separator permits operation for more or
less extended periods by limiting the inter-
30 diffusion of the products in the anodic and
cathodic compartments. Nevertheless inter-
diffusion occurs to a sufficient extent so that
operation of the cell must be stopped more or
less frequently for cleaning.

It is the object of the present invention to
35 avoid the difficulty experienced in the opera-
tion of cells of the character described and
to permit substantially continuous opera-
tion thereof for much longer periods by pre-
venting the interdiffusion of the anode and
40 cathode liquors in a more thorough manner.

A further object of the invention is the
provision of an improved electrolytic cell
and of a novel method of operating such a
cell to permit the simultaneous production of
45 solutions of alkalies and of metallic salts in a
substantially continuous manner.

I have discovered that interdiffusion in
electrolytic cells designed to permit the pro-
duction of solutions of metallic salts and the
50 alkalies can be prevented by maintaining an

independent body of the electrolyte between
the anode and cathode compartments and by
constantly renewing this body of electrolyte.
This independent protecting body of electro-
lyte provides a meeting place for the metallic
55 salt and alkali diffusing from the anode and
cathode. The incipient precipitate in the
protecting body of electrolyte is swept out
by the continuous withdrawal of this electro-
lyte. Ordinarily the electrolyte with-
60 drawn from the protecting body contains a
little of the metallic salt and no alkali. It is
possible thus to prevent the concentration of
the metallic salt in the protecting body of
electrolyte from increasing beyond from 0.1
65 to 0.3 normal while the anode liquor is from
2 to 3 normal.

In carrying out the invention I provide a
cell having preferably a central anode and
perforated cathodes at the sides thereof with
diaphragms such as asbestos sheets disposed
at the cathodes to limit the flow of the elec-
70 trolyte therethrough. I provide in addition
spaced separators between the anode and
cathodes. These separators may be made
likewise of asbestos sheets or of asbestos and
paper with a fabric such as burlap. The
75 separators are spaced apart, for example,
about five-eighths of an inch so as to form
an intermediate compartment between the
anode and cathode compartments. Each of
the individual compartments is supplied
80 constantly with the electrolyte from sources
maintained at a constant level so as to ensure
the same head of liquor in each compart-
ment. Provision is made for the withdrawal
85 constantly of the anode liquor and of the
electrolyte from the intermediate compart-
ments. Such provision may include outlet
pipes with nozzles of predetermined dimen-
90 sions designed to ensure a constant flow of
the desired proportion. The electrolyte
which passes through the cathode dia-
phragms is likewise withdrawn as it is
95 formed and constitutes the alkali solution
which is one of the products of the operation.

The constant flow of the electrolyte through
the intermediate compartments ensures the
maintenance therein of protecting bodies of
electrolyte which are only slightly contami-
100

nated with the anode liquor. The formation of precipitates in the anode and cathode compartments is thus avoided and the operation of the cell is improved materially.

5 The invention as described can be utilized in various electrolytic operations wherein it is designed to produce simultaneously solutions of compounds which would react if permitted to contact with each other. The 10 invention is particularly useful in the production of solutions of alkalies and of metallic salts, for example, the electrolysis of sodium chloride in the presence of an iron anode to produce ferrous chloride and sodium hydroxide as described in the Letters Patent aforesaid. Other electrolytes may be used, however, such as sodium sulphate which may be substituted for sodium chloride. Similarly other soluble salts of the 15 alkali metals such as sodium nitrate, sodium bromide, sodium acetate, potassium chloride, etc., may be electrolyzed in the cell as described to produce solutions of the alkalies and of metallic salts. Moreover, by replacing the iron anode by one of zinc, nickel or some other metal which forms a chloride, sulphate or other salt, soluble in water but which is itself insoluble in that menstruum, other metallic salts can be obtained along 20 with the alkalies. The products may be recombined in accordance with the method of the Letters Patent aforesaid and of other patents issued to me heretofore for the production of pigments by regulated oxidation 25 of freshly precipitated ferrous hydroxide. They may be used also for any other purpose for which they are adapted and they are particularly desirable for many purposes because of their relatively high purity.

30 40 The invention will be described in more detail with reference to the accompanying drawing, in which

45 Fig. 1 is a transverse section through a cell constructed in accordance with the invention;

Fig. 2 is a longitudinal section through the cell;

50 Figs. 3 and 4 are end elevations of the cell; and

Fig. 5 is a detail in section showing the construction of one of the separators.

55 Referring to the drawing, 5 indicates a base constructed of concrete, for example, or of other material which is not affected by the anode liquor. A plurality of rods 6 extend upwardly from the base and support a frame 7 forming the top of the cell. A plurality of frames 8, 9 and 10 are supported on the concrete base and are secured by clamps 11 thereto. The frames are held at the top of the cell by screws 12 supported in bars 13 which extend lengthwise of the cell on the frame 7. Plates 14 are secured to the sides of the cell 60 and are held by the clamps 11 and screws 12,

these plates forming the compartments into which the alkali solution flows through the perforated cathode plates 15 which are similarly supported. Diaphragms 16 preferably of asbestos paper are likewise supported 70 adjacent to the cathode plates 15 to limit the flow of the electrolyte through the cathode plates.

75 Separators 17 are supported in spaced relation by the frames 8 and form the intermediate compartments of the cell, the space between each of the diaphragms 16 and the adjacent separators 17 being defined in such a manner by the separators that the electrolyte therein comprises a catholyte. These 80 separators may be constructed of any suitable material, but preferably may comprise an inner sheet of asbestos paper 18 with layers 19 of cellulose paper thereon and protecting layers 20 of a fabric such as burlap to 85 give additional strength to the separators.

90 The anodes 21 are supported by holders 22 in the anode compartment 23 and are connected by conductors 24 to a source of current of a character suitable for the practice of the electrolytic operation. The cathodes 15 are likewise connected by a conductor 25 to the source of current. In operation the several compartments of the cell are supplied with the electrolyte, for example, a saturated solution of sodium chloride from constant level 95 containers 26 disposed at the ends of the cell. The electrolyte is delivered to these containers through pipes 27 and overflows through orifices 28 to compartments 29 whence it may 100 be returned again to the constant level containers. The electrolyte enters the several compartments through pipes 30, 31 and 32 provided for that purpose. The liquor in the anode compartment which, in the case of iron anodes and a sodium chloride electrolyte, consists of a concentrated solution of ferrous chloride, descends into a chamber 33 in the base 5 and escapes through an outlet 36 having a nozzle 37 at the end thereof, the 105 orifice of which is of such size as to ensure the continuous flow of the desired proportion of the anode liquor from the cell. Similarly the electrolyte which enters the intermediate compartments flows therefrom constantly 110 through an outlet 38 having a similar nozzle 39 to ensure the constant flow of the desired proportion of the liquid from the cell. The electrolyte which enters the cathode compartments passes through the diaphragms 16 and is converted at the cathode into the alkali solution, for example, sodium hydroxide. It 115 is withdrawn as formed through pipes 40 provided for that purpose.

120 In the operation of the cell as described 125 constantly renewed bodies of the electrolyte are maintained between the anode and cathode compartments. Fresh electrolyte is delivered constantly to the intermediate compartments, and being substantially free from 130

the salt produced in the anode compartment or containing only a very low concentration of such salt, it effectually prevents diffusion of that salt into the cathode compartment and avoids the separation of an appreciable precipitate therein. Diffusion of the alkali into the anode compartment is prevented similarly. Consequently, when properly operated the cell as described can be used for long periods without the necessity of dismantling it for cleaning, it being necessary only to renew the anodes as they are dissolved and to ensure the maintenance of fresh electrolyte in the intermediate compartments. Another advantage of the cell is its simplicity of construction and the relatively slight attention which it requires during operation. The rate of outflow of the solutions when once determined remains fixed and a constant head of electrolyte is supplied to all of the compartments from the constant level receptacle. Consequently it is necessary only to ensure a supply of the electrolyte to the constant level compartments and the maintenance of the current supply. The only other attention required is the renewal of the anodes as the latter are used up by the operation.

While I have described the particular application of the invention to the production of ferrous chloride and sodium hydroxide, it is to be understood that the invention has a broader application and that, moreover, the structure of the cell may be varied to meet particular requirements. The important features of the invention are the maintenance of the protecting intermediate layers of the electrolyte between the anode and cathode compartments and the provision in the cell for such layers and the renewal thereof so that increase in the concentration of the salt produced in the anode compartment may be avoided.

Various changes may be made, therefore, in the details of arrangement of the apparatus and in the mode of operation thereof without departing from the invention or sacrificing any of its advantages.

I claim:-

1. The method of conducting electrolysis with a soluble anode, which comprises continuously supplying fresh electrolyte to an independent body thereof between bodies of electrolyte in contact with the anode and cathode, separately supplying electrolyte to the latter bodies and continuously withdrawing a portion of the electrolyte from the independent body without contact with the anode or cathode.

2. The method of conducting electrolysis with a soluble anode, which comprises separating bodies of electrolyte in contact with the anode and cathode by an independent body of electrolyte, withdrawing a portion thereof continuously without contact with the anode or cathode and replenishing the independent

body to avoid increased concentration of the anode product therein and separately supplying electrolyte to the bodies thereof in contact with the anode and cathode.

3. An electrolytic cell comprising the combination with a soluble anode of a perforated cathode at one side of the cell, a porous diaphragm closely adjacent the cathode, spaced porous separators between the anode and the porous diaphragm dividing the cell into separate anode and cathode compartments and forming an intermediate compartment and means for supplying electrolyte to and withdrawing products separately from the several compartments.

4. The method of simultaneously producing solutions of metal salts and alkalies which comprises electrolyzing a solution of an alkali salt in the presence of a soluble anode and a cathode, separating the bodies of salt solution in contact with the anode and cathode by an independent body which is constantly renewed without contacting the anode or cathode, and separately supplying salt solution to the bodies thereof in contact with the anode and cathode.

In testimony whereof I affix my signature.
PETER FIREMAN.
